F. MANKEY.

PANEL.

No. 16,232.

Patented Sept. 8, 1885.

UNITED STATES PATENT OFFICE,

FREDERICK MANKEY, OF WILLIAMSPORT, PENNSYLVANIA.

DESIGN FOR A PANEL.

SPECIFICATION forming part of Design No. 16,232, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and 5 original Design for Panels, of which the following is a specification, reference being had to the accompanying photographs, forming part thereof.

Figure 1 is a plan view of my design. Fig. 10 2 is a longitudinal section of the design with elevations D E F G, and is here presented to show the contour of said elevations.

My design relates to an ornamental panel for doors, wainscots, furniture, &c.; and it consists in an ornamental figure, A, such as here shown, within the raised rectangular frame B. The frame B has curved or rounded edges C. D, E, F, and G are series of elongated elevations, each series occupying about one quarter 15 20 of the panel and placed diagonally thereon in directions parallel to the sides of the central

frame B. The upper sides of the elevations D E F G are rounded, as indicated on Fig. 2, and between said elevations are spaces or channels F'. 25

The precise central figure A here shown is not material to my design, as I may vary the same and employ any other suitable ornamental device.

I claim—

The design for a panel, substantially as herein shown and described, consisting in a central figure, A, a rectangular frame, B, around said figure, with rounded or curved edges C, and parallel to the sides of said frame series 35 of elevations D E F G, having upper rounded sides and intermediate channels. 30

FREDERICK MANKEY.
